(57) CLAIM

The ornamental design for an earcup for a headset, as shown and described.

DESCRIPTION

This invention was made with Government support under SBIR contract N68335-09-C-0003, awarded by the US Navy. The government has certain rights in the invention.

FIG. 1 is a perspective view of the earcup of the present invention. The approximately oval center area in FIG. 1 is a solid surface.

FIG. 2 is a side view of the earcup.

FIG. 3 is a side view of the earcup, showing the opposite side from FIG. 2.

FIG. 4 is a top view of the earcup.

FIG. 5 is a side view of the earcup, showing the side facing away from a wearer's head when the earcup is worn as part of a headset. The approximately oval center area in FIG. 5 is a solid surface.

FIG. 6 is a bottom view of the earcup. The broken lines form no part of the claimed design; and,

FIG. 7 is a side view of the earcup, showing the side facing toward a wearer's head when the earcup is worn as part of a headset. The approximately oval center area in FIG. 7 is a hole into the interior of the earcup.
